Attorney

UNITED STATES PATENT OFFICE.

GEORGE KOLLSTEDE, OF PROVIDENCE, RHODE ISLAND.

ORNAMENTAL CHAIN.

Application filed August 4, 1925. Serial No. 48,046.

To all whom it may concern:

Be it known that I, GEORGE KOLLSTEDE, a citizen of the United States, residing at Providence, in the county of Providence and

5 State of Rhode Island, have invented certain new and useful Improvements in Ornamental Chains, of which the following is a specification.

10 My invention relates to ornamental chains such as expansible bracelets, linkages, bands, girdles, and garters, of the hollow unit type.

15 The essential objects of my invention are to enable the bodily detachment of any link or unit from a chain of the above type without the necessity of moving or twisting the link to be removed into an angular position relatively to the remainder of the chain, and to attain these ends in a strong, 20 simple, and inexpensive structure.

25 My invention consists in the construction, means, and mechanism for producing the results above specified substantially as herein-after claimed.

30 In the accompanying drawings which form a part of this specification, and wherein like reference characters indicate like parts throughout the views,

Figure 1 is a fragmentary rear elevation 35 of a chain or bracelet embodying my invention,

Figure 2, a section of the same on line 2—2 of Figure 1,

Figure 3, an enlarged section on line 3—3 of Figure 2,

Figure 4, a section on line 4—4 of Figure 1, and

Figure 5, an enlarged perspective view of one of the connecting units.

40 My chain as herein illustrated includes outer tubular or hollow link members or units, and enclosed connecting link members or units, indicated in a general way by 10 and 11 respectively. Each unit 10 com-

45 prises a transversely curved front plate 12 with its lateral edges rolled over upon a transversely curved back plate 13 to form marginal beads 14. Integral with the ends of the plate 12 are inwardly bent flanges

50 forming the end walls 15 provided with centrally cut away portions forming openings 16. The ends of each back plate 13 are inwardly turned at right angles to form the

walls 17 provided with peripheral cut away portion or of less height than the walls 15, 55 thus forming resultant arcuate openings 18 registering with the openings 16.

Each connecting unit 11 comprises an oblong transversely curved plate or body 19 provided with lateral guide shoulders 20. 60 One end of the plate is bent at right angles to form a flange 22. Near its other end there is cut from the material of the plate 19, forming a resultant opening 23, a transversely disposed inclined resilient tongue 24. 65

As assembled each unit 11 passes through the openings 18 in the end walls of the units 10. A helical spring 26 in each unit has one end pressing against its wall 17, and its other end abutting against the flange 22. 70 In the adjacent unit the tongue 24 is rearwardly directed and in transverse alignment with the hole 27 near the end of the back wall 13. In order to free the adjacent unit it is merely necessary to forwardly 75 press the tongue 24 into the plane of the openings 18 and the action of the spring 26 will automatically withdraw the unit 11 with its depressed tongue from the adjacent unit. A convenient implement for this 80 purpose is a pin or other pointed tool 28 indicated in Figure 2 wherein the broken lines show the depressed position of the tongue 24.

It will be observed that the removal of a 85 unit by the described operation does not require any slow and laborious tilting or twisting of either the unit to be removed or any remaining portion of the chain. Nor can the chain accidentally come apart by 90 any twisting or turning or tilting motion.

I claim,

In a device of the type specified, a series of hollow connected units provided with openings in their ends, slidably connecting plates in the units extending through the openings, flanges upon the corresponding ends of the plates, compressible tongues upon the opposite ends of the plates, the units being provided with holes in substantial alignment with the tongues, and springs engaging the flanges and the adjacent ends of the units. 100

In testimony whereof I have affixed my signature.

GEORGE KOLLSTEDE.
